(57) **ABSTRACT**

Disclosed herein are various methods and devices for modifying the comfort and performance characteristics of a shoe. In various embodiments, the devices are soles, insole or outsoles, of a shoe comprising one or more shocks. The shocks may be defined by shock cavities positioned within one or more surfaces of a sole. In some embodiments the shock cavity may be configured to receive one or more shock cavity inserts.

MANUAL AND DYNAMIC SHOE
COMFORTNESS ADJUSTMENT METHODSCROSS-REFERENCE TO RELATED
APPLICATION

This application claims the benefit under 35 U.S.C. § 119 of the earlier filing date of U.S. Provisional Application Ser. No. 62/279,343 filed on Jan. 15, 2016, the entire contents of which are hereby incorporated by reference in their entirety for any purpose.

FIELD

The disclosed processes, methods, and systems are directed to modifying the comfort, fit, and performance characteristics of a shoe.

BACKGROUND

While shoes are often fashion statements, a well-designed shoe should protect the foot without causing discomfort. In general, the comfortability of a shoe is determined by the fit (for example the size) and the footbed. The footbed comprises an insole and an outer sole. The footbed being positioned below the foot to provide support and cushioning when the shoe contacts a walking surface (pavement, ground, etc.). The insole is designed to be in direct contact with the lower surface of the foot and the outer sole is designed to contact the walking surface (e.g. the ground). However, the footbeds of most shoes do not offer enough support for the foot, in general or the arch, ball, or heel of the foot, in particular. Additionally, some outsoles may not provide for enough traction with the ground.

Studies demonstrate that the positioning of a foot inside a shoe is a large determinant in the overall long-term health of the foot. Additionally, the angle at which a foot rests inside a shoe often determines the comfortability of a shoe for the wearer. This may be due to the angle at which a person's foot should rest inside a shoe differs from person to person.

As a result, there is need for shoes that contain footbeds that are adjustable. The present disclosure is designed to address that need.

SUMMARY

Disclosed herein are devices and methods for increasing the comfort of a shoe. In one embodiment the device comprises, a sole having a first and a second surface, two or more shocks, extending away from the first surface of the sole, the shocks defining a first end positioned at or near the first surface of the sole and a second end positioned away from the first surface of the sole, a shock cavity defined by two adjacent shocks and the first surface of the sole, wherein the two or more shocks define two or more shock angles, and the shock cavity defines a shock cavity angle, and wherein the sole is an insole that lies along a footbed of the shoe and designed to contact a user's foot, or the sole is an outsole positioned at a bottom of the shoe and makes contact with the walking surface. In some embodiments, the sole may further comprise a bumper material to allow the sole to be used within a series of shoes sizes, and the device may further comprise at least one displacement translator positioned within at least one cavity, and at least one support structure, wherein the displacement translator is substantially flat and connected to the support structure.

2

Also disclosed are methods of embedding additional shock absorption properties to a material, the method comprising the steps of creating a sole of a shoe comprising a first material having a first shock absorption property, altering the first shock absorption property of the sole through the creation of the individual shock cavities within the sole, and adding a shock cavity insert into an individual shock cavity and further altering the first shock absorption property, wherein the shock defines a first shock angle, and the shock cavity insert defines a first shock cavity angle, and a plurality of shock cavity inserts are added to the individual shock cavity, which are dissimilarly shaped. In some embodiments the shock cavity insert is made of a second material having a second shock absorption property, or the first material and the second material are the same, or the second material is made from a plurality of materials. In some embodiments, the first shock absorption property and the second shock absorption property are similar.

Also disclosed is a device to modify the shock impact absorption properties of an item worn on a foot, the device comprising, an insole having a first layer positioned above a second layer, the first layer having an upper surface and a lower surface, the second layer having an upper surface and a lower surface, an outsole positioned below the insole and having an upper surface and a lower surface, wherein a plurality of a first shock cavities are formed beneath openings in the lower surface of the second layer and between first shocks, the cavities extending towards the upper surface of the second layer, wherein the first shock defines a first shock angle, and the first shock cavity defining a first shock cavity angle, and, in some embodiments, further comprising a first shock cavity insert positioned within a portion of at least one of the first shock cavities, or a plurality of second shock cavities formed beneath openings in the upper surface of the surface of the second layer and between the second shocks, the cavities extending towards the lower surface of the second layer, which may further comprise a second shock cavity insert positioned within a portion of at least one of the second shock cavities. In some embodiments, the device further comprises a first leaf spring insert positioned adjacent to and beneath the lower surface of the second layer, wherein a portion of the first leaf spring insert extends into the first shock cavities, or the second leaf spring insert is positioned adjacent to and above the upper surface of the second layer, wherein a portion of the second leaf spring insert extends into the second shock cavities. In some embodiments, the device may further comprise a plurality of third shock cavities formed beneath openings in the lower surface of the outsole, the third shock cavities extending towards the upper surface of the outsole, or a plurality of fourth shock cavities formed beneath openings in the upper surface of the outsole, the fourth shock cavities extending towards the lower surface of the outsole.

BRIEF DESCRIPTION OF THE DRAWINGS

FIGS. 1A-1D are representative embodiments of an insole according to the present disclosure.

FIGS. 2A-2B are representative embodiments of shock cavity inserts according to the present disclosure.

FIGS. 3A-3B are additional representative embodiments of an insole according to the present disclosure.

FIG. 4A is an additional representative embodiment of an insole, and FIG. 4B is a shock cavity grid patterns on the outsole or insole.

FIGS. 5A and 5B are representative embodiments of the shock cavity grid patterns on the outsole or insole.

FIG. 6 is a representative embodiment of a clustering shock cavity grid pattern on the outsole or insole.

FIGS. 7B-7C are representative embodiments of the outsole shock cavities.

FIG. 8 is a representative embodiment of shock cavities on the insole and outsole of an embodiment.

FIGS. 9A-9B are representative embodiments of an insole according to the present disclosure.

FIG. 10 shows various representative embodiments of the shock cavity inserts.

FIGS. 11A-11C are representative embodiments of shock cavities on both sides of a sole (insole or outsole).

FIGS. 12A-12C are representative embodiments of different shock cavities formed with leaf springs.

FIGS. 14A-14B are representative embodiments of bowl shape shocks.

FIGS. 15A-15B are representative embodiments of the present disclosure showing secondary displacement translator systems.

FIGS. 16A-16C are representative embodiments of one type of disclosed secondary displacement translators.

FIGS. 17A-17B are representative embodiments of a sole according to the present disclosure.

FIGS. 18A-18B are an example of a shoe having various features according to the present disclosure.

FIGS. 19A-19B are another example of a shoe having various features according to the present disclosure.

FIGS. 20A-20B are another example of a shoe having various features according to the present disclosure.

FIGS. 21A-21B are another example of a shoe having various features according to the present disclosure.

DETAILED DESCRIPTION

Disclosed herein are devices, methods, and systems for increasing the comfortability of a shoe. In some embodiments, the shoes allow for customization of the shoe to conform to the wearers' wishes and needs.

Several problems are solved or reduced by the presently disclosed devices and methods. In some embodiments, the disclosed devices, methods, and systems allow for dynamic shock absorption. For example the disclosed methods and devices may aid in (1) reducing foot, knee, or pelvic/hip joint pain, (2) reducing pain at prostheses-limb contact surfaces, (3) adjusting leg length for people with unequal length legs, (4) allowing the user to feel as if they were walking on an air mattress or a gymnastics mat, (5) improving and adjusting foot support due to shock cavity and shock cavity inserts properties, (6) auto-ventilating the shoe and/or foot to reduce foot and shoe odors as well as moisture buildup in the shoe, (7) reducing the abrasive friction of heel and shoe, (8) solving an age-old problem of the lack of high-displacement dynamic shock absorption insoles.

The present disclosure relates to an adjustable sole consisting of multiple shocks protruding away from the sole, creating a number of crevices in between the shocks known as shock cavities. Within these shock cavities, adjustable shock cavity inserts can be placed to control the comfortability and shock absorption.

Sole

FIG. 1A is a view of an embodiment of an insole taken along line 1A-1A of FIG. 10. The term sole 100 can refer to an insole 102 or an outsole 104 (see, e.g., FIG. 4A). A sole 100 may have one or more parts, for example, as depicted in FIGS. 1A, 1C, and 1D, an insole 102 may have a first, or top layer/part 106, and a second, bottom layer/part 108. In other examples, a cross-sectional view of the sole 100, such as an

insole 102 or outsole 104, may have another configuration, such as those described in FIGS. 9A and 9B. The top part 106 of the insole 102 may define a top surface 110 for contacting and/or supporting a foot, the bottom surface 111 of the first part 106 for contacting the second, bottom part 108. The bottom part 108 may define a top surface 120 for contacting and/or supporting the first part 106 of the insole 102, and a bottom surface 121 for contacting a shoe. The sole 100 includes a toe end 124 and a heel end 126. The toe end 124 is designed to be located at or near the toes of the foot, and the heel end 126 designed to be located at or near the heel end of the foot. In various embodiments, the sole 100 may be about the length of the foot and/or shoe. In some embodiments, the sole 100 may be about half the length of the foot or shoe. The sole 100 may define a plurality of shock cavities 112 that are formed between shocks 114 formed in the sole 100. FIG. 1B is an expanded view of a portion of the shock cavities 112 and shocks 114 of FIG. 1A

Shock cavities 112 may be defined in a top surface 110, 20 120 (see FIG. 9A) of the sole or the bottom surface 111, 121 (see FIG. 9B) of the sole. The shock cavities 112 may form an orderly or random grid with various spacing and patterns, as shown in FIGS. 4B-6A. In some embodiments, the toe end 124 of the sole 100 may have more shock cavities 112 25 than the heel end 126 and vice-versa, as shown in FIG. 6.

One embodiment of an insole 102 is depicted in FIG. 1A. FIG. 1A depicts a two-part insole having a first layer 106 and a second layer 108 wherein layer 106 is a first, top part designed to contact a foot on the upper surface 110. Layer 106 may absorb the impact of shock forces generated by the user, but does not have shock cavities and thus may have limited shock absorption properties. The second layer 108 is a lower part and defines a shock layer with a plurality of shock cavities 112 and shocks 114. FIG. 10 is a perspective view of a second layer. The shock cavities 112 and shocks 114 of layer 108 may be designed for accepting the impact of shock forces generated by the user. Shocks 114 and shock cavities 112 are discussed further below and in relation to FIGS. 2A-2B.

Shock

Shocks 114 may aid in providing support for the sole 100 of a shoe, as well as providing for the creation of shock cavities 112 to adjust the shock force absorption of the sole 100 and the shoe and other material properties. Shock cavity inserts 116a, 116b may be positioned within a shock cavity 112, as shown in FIG. 2A. In other examples, the shocks may have a different configuration, such as those described in FIGS. 1A, 3A, 7B, 8, 9A, 9B, 11A, 12A-12C, 14A-14B, 15A, 15B, 17A, 16A-16C, 18A, 19A, 20A, and 21A. A shock 114 may be defined by the structure between adjacent shock cavities 112, which may or may not be designed to accept a shock cavity insert 116. Shocks 114 may extend from a surface 107 of the sole 100 at an angle Θ measured from vertical, away from the plane of the surface. The value of angle Θ may vary for different embodiments, similar embodiments using different materials, similar embodiments using different insole sizes, and to meet certain user comfort requirements. In many embodiments, the value of angle Θ may vary from 0 to 45 degrees, and in preferred embodiments may vary from 5 to 45 degrees.

One embodiment of a shock 114 is depicted in FIG. 1A. FIG. 1A depicts the shock cavities 112 defined in second layer 108 of an insole 102. The shock cavities 112 of layer 108 extend away from the first layer 106 at an angle Θ measured from vertical. The shock 114 and shock cavity 112 may embody various characteristics, for example length, width, stiffness, compressibility, value of angle Θ , etc. FIG.

7B further depicts the angle Θ of the shock cavity 112 and shock 114 measured from vertical and the angle ω of the shock cavity insert 116 (see below). In many embodiments, the angle Θ of the shock cavity 112 and shock 114 and the angle ω of the shock insert 116 may be equal. In other embodiments, the value of angle Θ of a shock cavity 112 and shock 114, at a particular location, may be different at another location, such that the angle Θ varies at different locations of the sole 100. In some embodiments, the characteristics of a shock cavity 112 may be dependent on the sizes or walls of the shock 114 that define the shock cavity 112 as well as the spatial arrangement of shock cavities 112. The various characteristics of a sole 100 may differ, and in some cases may be adjusted, to allow for greater user discretion in choosing the overall character of the shoe. For example, various combinations of characteristics may allow the user to select an insole 102 or outsole 104 for its comfort and/or its performance characteristics. The ability to select these combinations may lead to enhanced comfortability of a shoe.

The shock may be comprised of various parts. As depicted in FIG. 1B, the shock may have an upper part/portion 152, positioned at or near a shock cavity opening 150. The shock may have a lower portion 156, positioned distal to the opening 150. The shock may define a surface 154 at the upper portion 152, and a second surface 158 at the lower portion 156. The shock may also define a width, D_1 , measured from one surface in one cavity 112 to a similarly positioned surface in an adjacent cavity. The shock may also define a depth, L_1 , measured from the surface 111 of the sole at or near the opening 150, to the base 160 formed by the surface 107. In some embodiments, as shown in FIGS. 1A and 1B, the depth, L_1 , may change when measured near one surface in one cavity and then the adjacent cavity. In other embodiments, the depth is constant. In some embodiments, the shock may be removable.

Shock Cavity

The property of a shock cavity 112 may depend on orientation (angle), dimensions shape, grid pattern (e.g. distance between adjacent shock cavities 112, number of cavities 112 per unit of area), and properties of the material between the shock cavities 112 (e.g., shock 114 material). These properties—such as density, elasticity, and rebound—as well as shock cavity insert 116 dimensions may help to control feel, displacement (horizontal and height) and shock force absorption.

Referring again to FIG. 1B, which depicts a shock cavity from FIG. 1A. In this embodiment, the shape of the shock 114 may help define the shape of the shock cavity 112. The shock cavity 112 may be defined by the opening 150 in the sole, here an outsole 104, and two adjacent shocks 114. The shock surfaces 154, 158, and a lower surface 162, positioned at or near the lower portion 156 of the shock help to define a shock cavity volume. The shock cavity may also define a width, D_2 , measured from one surface (e.g. 158) to a similarly positioned surface on the other side of the cavity. The shock cavity may also define a depth, L_2 , measured from the opening 150, to the base surface 162. In some embodiments, as shown in FIGS. 1A and 1B, the depth, L_2 , may vary, for example from one end of the cavity and the other (see also FIG. 2A). In other embodiments, the depth is constant. In some embodiments, wherein the cavity is cylindrical, the width, D_2 , may be a diameter, which in some embodiments may differ from the upper portion to the lower portion (again, see FIG. 2A).

In some embodiments, the shock cavity 112 defines a cylindrical shape. In other embodiments, the shock cavity

112 defines various other shapes. In some embodiments, as shown in FIGS. 11A-11C, the shock cavity 112 defines a shape that is other than cylindrical. In these embodiments, the shock cavity may be rectangular or trough-like.

5 FIGS. 11A-11C further depict an embodiment of the disclosed sole 100, for example an insole 102, with shock cavities 112 defined in the upper surface 110 and the lower surface 111 of the first layer 106 of the insole 102. In this embodiment, the lower surface 111 defines a plurality of shock cavities 112 extending toward the upper surface 110 of the insole 106, while the upper surface 110 of the insole 106 defines a plurality of shock cavities 112 that extend toward the lower surface 111. In these embodiments, the shock cavities 112 of one surface may extend into the shocks 114 of the other surface. In other embodiments, the shock cavities 112 of one surface do not extend into the shocks 114 of the other surface.

The shock cavity 112 may be designed to accept a shock cavity insert 116. In many embodiments, the shock cavity 20 112 insert 116 may define a shape that may aid in retaining a shock cavity insert within the shock cavity. One embodiment of a shock cavity 112 for retaining a shock cavity insert 116 is depicted in FIG. 2A with the second layer 108 of an insole 102. In FIG. 2A, the shocks 114, shock cavities 112, and the shock cavity inserts 116 are formed in the lower surface 121 of layer 108.

Referring to the shock cavity 114 embodiment of FIG. 2A, the width of the base 160b between the shocks 114 maybe wider than the opening 150 to aid in retaining a shock 30 cavity insert 116 within the shock cavity 112.

Shock Cavity Insert

Shock cavity inserts 116 may be designed to occupy a volume of the shock cavity 112 defined by the surrounding shocks 114. With reference to FIG. 2B, in some embodiments, the shock cavity insert 116 may define an outer surface 170 that is in contact with or adjacent to the upper surface 154, lower surface 158, and base surface 162 that form the shock cavity 112. In some embodiments, the shock cavity insert 116 may not occupy all of the volume of the shock cavity 112—in these embodiments there may be a distance between the surface of the shock cavity insert 170 and the surfaces that form the shock cavity 112. In some embodiments, the surface 170 of the shock cavity insert 116 may contact the surfaces 154, 158, 160 that form the shock cavity 112 at some positions but not others. In some embodiments, multiple shock cavity inserts 116 may be inserted into one shock cavity 112, which may result in increasing the overall density of the combined shock cavity inserts 116. This may make the effective insert less compressible, and therefore increase the firmness of the shock cavity insert 116.

In many embodiments, the dimensions of the shock cavity insert may be similar to the dimensions, D_2 and L_2 , of the shock cavity. In other embodiments, the shock cavity 55 insert's dimensions may be a percentage of the corresponding dimensions of the shock cavity. For example the dimensions of the shock cavity insert may be from about 80%-105% of the corresponding dimensions of the shock cavity in any one or more positions. In some embodiments, the dimensions may be uniformly different, and in other embodiments, one dimension may be one value and a second dimension may be another—for example the depth may be about 90% while the width is 101%. In many embodiments, the dimensions of the shock cavity insert may be greater than 60 about 80%, 85%, 90%, 91%, 92%, 93%, 94%, 95%, 96%, 97%, 98%, 99%, 100%, 101%, 102%, 103%, or 104%, and less than about 105%, 104%, 103%, 102%, 101%, 100%,

99%, 98%, 97%, 96%, 95%, 94%, 93%, 92%, 91%, 90%, or 85% that of the corresponding dimension of the shock cavity. In some embodiments, for example embodiments where a shock insert is compressible, such as where the insert is made of a compressible foam material, the shock insert may define a volume, when uncompressed, that is greater than 100% the volume of the cavity. For example, in these embodiments, the difference may be greater than 105%, 110%, 120%, 130%, 140%, 150%, 160%, 170%, 180%, 190%, 200%, or 300%, and less than about 350%, 300%, 250%, 200%, 190%, 180%, 170%, 160%, 150%, 140%, 130%, 120%, or 110%. In some embodiments, for example wherein the density of the insert's material is the same or similar to the sole material's density, the volume difference may be from about 80% to about 120%. In embodiments wherein the insert is made of a silicone or a gel material, the volume of the shock insert may be about 95% to about 105% of the shock cavity's volume.

The shock cavity insert 116 may define various shapes, which may correspond to the shapes defined by the shock cavity 112. While many embodiments of shock cavity insert 116 may be cylindrical to correspond to a cylindrical shock cavity shape, such as shock cavity insert 116g of FIG. 10, other embodiments may be shapes other than cylindrical. FIG. 10 shows shock cavity insert embodiments that are oblong and rectangular, such as 116f. FIG. 10 also shows a concatenated shock cavity insert 116h with oblong subunits, wherein the oblong subunits are stacked atop each other to form a shock cavity insert 116h.

Shock cavity inserts 116 may be comprised of various materials. In some embodiments, the shock cavity insert 116 may be hollow, such as the cross-sectional view of 116i of FIG. 10 or may define an interior material that is different than the exterior material of the shock cavity insert. In some embodiments, the interior of the shock cavity insert 116 is solid, liquid, or gas. The selection of the material or materials of the shock cavity insert 116 may aid in changing the performance characteristics of the shock cavity insert 116. In some embodiments, the material may be selected from ethylene-vinyl acetate (EVA), rubber, silicone, gel, or any material having sufficient shock absorbing properties.

Shock cavity inserts may also define an angle similar to Θ . In many embodiments, this angle, ω , may correspond to the angle Θ for the cavity where a specific shock cavity insert resides. In many embodiments, such as the embodiment of FIG. 2A, where the shock cavity insert has a non-uniform structure, w may be defined by the angle of the insert at or near the opening 150 of the shock cavity. As described above, in many embodiments, angle ω may be the same or similar to angle Θ . That is in most embodiments, angle ω is about 0 degrees to about 45 degrees, and in preferred embodiments is between about 5 degrees and about 45 degrees.

Referring to FIG. 7B, the angle Θ of the shock cavity 112 may aid in redirecting the directional forces associated with an impact. During the process of compression, as the foot presses on the sole 100, the angle Θ , together with the shock 114 and shock cavity insert 116 may help the shock cavity 112 gracefully collapse. In many embodiments, compression changes the angle Θ position. In the case of an insole 102, the angle Θ is selected so that compression and collapse of the shock cavity 112 may help to redirect the foot away from the heel end 126 of a shoe, reducing contact of the heel of the foot with the shoe, as shown in FIG. 17B. The angle Θ may be dependent on properties of sole materials, physical structure of the shock cavities 112, and relative spacing between adjacent shock cavities 112 formed by the shocks

114, and shoe size, which may be an indicator of the user's weight. In addition, it is possible to improve shock impact absorption performance and feel by adding multiple distinct angle Θ values to a given sole 100. This may be desirable for 5 having different shock absorption properties as deformation spreads from the center of impact.

Referring to FIG. 2B, shock cavity inserts 116 may comprise one or more subunits 118. The subunits 118 may be designed to fit together, and may aid in customizing the 10 performance of the shock cavity insert 116. In some embodiments, two or more shock cavity inserts 116 may be made of the same or different materials. In some embodiments, the subunits 118 of a single shock cavity insert 116 may be of the same or different materials. The material or materials 15 from which a shock cavity insert 116 is made may aid in modifying the performance of the shock cavity insert 116 and the insole 102. FIG. 2B shows a shock cavity insert with multiple subunits, 118a, 118b, 118c, 118d, 118e, demonstrating the adjustability of the composition of a shock 20 cavity insert 116. In this embodiment, the length of the shock cavity insert 116 may be varied by varying the number and depth, d, of the individual subunits.

FIG. 2A shows an example bottom layer 108 of an insole 102 with shock cavities 112 and shock cavity insert 116 25 embodiments, as well as the shock cavity at angle Θ . The embodiment on the left of FIG. 2A shows a shock cavity insert 116a and a shock cavity 112a without a visible means of retaining the shock cavity insert 116a within the shock cavity 112a. The embodiment on the right of FIG. 2A has a lower portion 156b of the shock cavity 112b, adjacent to the base 160b, defining a structure 157 to aid in retaining the shock cavity insert 116b in the shock cavity 112b with a similar, complementary structure. In addition to the shock cavity insert 116b complementary structure, the shock cavity 112b embodiment of FIG. 2A also depicts a retaining feature 30 35 157 of the shock cavity insert 116b. Many different forms of retaining features for shock cavity inserts 116 within a shock cavity 112 are contemplated. For example, shock cavities may be snapped, screwed, or pressed into the shock cavity via a screw lock, snap lock, or pressure lock.

FIG. 3B is a perspective view of the embodiment in FIG. 3A. In this view, the interior of the insole 106 is visible and the shock cavities 112 are cylindrical.

FIG. 3A is a sectional view along line 3A-3A of FIG. 3B 45 and depicts an embodiment of a first layer 106 of an insole 102 with a toe bumper 180. The toe bumper 180 may extend upward from the top surface 110 of the first layer 106 of the insole 102. In this embodiment, the toe bumper 180 is positioned at an edge at or near the toe end 124. The edge 50 55 of the insole 102 at the toe end 124 of this embodiment is curvilinear, and may be designed to correspond to the curvilinear shape or structure of a shoe. This embodiment further defines that the top surface 110 has a slope 182, such that the toe end 124 of the sole is closer to the ground (and 60 65 may be thinner) than the heel end 126, which may be thicker. This embodiment has only one part, wherein the top surface is designed to contact and support a foot, and the bottom surface defines a plurality of shock cavities 112. This configuration may also be used with an outsole 104 or a second layer 108. In other examples, a cross-sectional view of the sole 100, such as an insole 102 or outsole 104, may have another configuration, such as those described in FIGS. 11C, 15A, and 17A.

FIGS. 4A-4B show an embodiment of the insole 102 65 positioned atop a sole stiffener 184. As depicted in FIG. 4A, a side cross-sectional view of the shoe, with the insole 102 and sole stiffener 184. The sole stiffener 184 may rest on the

shoe foot bed, or outsole 104. In other examples, the sole 100, such as an insole 102, or outsole 104, may have a different configuration, such as those described in FIGS. 8, 18A, 19A, 20A, and 21A. In this embodiment, the sole stiffener 184 is positioned between the insole and the top surface of the shoe foot bed or outsole 104. The stiffener 184 may also aid in supporting or cushioning the insole 102. In some embodiments, as depicted in FIG. 4B, the stiffener 184 may be perforated, for example with one or more holes. In some embodiments the stiffener 184 may be stiff or rigid, or may be flexible and pliant. The holes of the stiffener may aid in enhancing shock impact absorption qualities of the shoe containing such a sole stiffener 184.

FIGS. 5A-5B show embodiments of the sole 100 wherein the shock cavities 112 may be arranged in a square (FIG. 5A) or an alternating (FIG. 5B) pattern. In many embodiments, the shock cavities 112 spacing or density may be substantially constant (FIGS. 5A and 5B). In some embodiments, the spacing or density of the shock cavities 112 may vary on the surface of the insole 102 or the outsole 104. For example, in some embodiments, the shock cavity 112 density may be increased at a position (for example near the heel) to aid in enhancing comfortability. FIG. 6 shows such an embodiment, wherein the density of shock cavities 112 is higher near the heel end 126 and the toe end 124.

FIG. 7C shows an embodiment of a shoe having an integral sole 100 or outsole 104 comprising shock cavities 112. In this embodiment, the shoe has an outer sole 104 that may define a plurality of shock cavities 112 positioned with the opening 150 of each shock cavity 112 at or near the ground.

FIG. 7B shows various embodiments of shock cavities 112c, 112d and shock cavity inserts 116c, 116d in cross-sectional view. In these embodiments the shock cavity insert is held in place by either a structure 157 having corresponding complementary features in both the cavity 112d and the shock cavity insert 116d or the shock cavity insert 116c is retained in the shock cavity 112c with an adhesion or connection apparatus 186, such as glue. As described above, securing a shock cavity insert 116 within a shock cavity 112 may be through an adhesion or connection apparatus 186 such as a snap lock, glue, pressure lock, or screw lock.

FIG. 8 shows an embodiment of the disclosed shock cavities 112 and shocks in an outsole 104 having shock cavities 112 and an insole 102 with shock cavities 112. Shock cavity inserts are not depicted in this embodiment. In some examples, the embodiment may be used in a sandal.

FIG. 10 shows additional embodiments of contemplated shock cavity insert structures 116a, 116b, 116c, 116d.

FIG. 9A shows an embodiment of the disclosed device having two parts. In this embodiment, the insole 102 comprises the second layer 108 with a lower surface 121 for contacting a support sole, ground, or footbed, and a first layer 106 designed to be supported by the second layer 108. In this embodiment, the first layer 106 is also designed, at least in part, to support a foot. The first layer 106 of the embodiment of FIG. 9A may be designed to support the back portion of the foot, while the front of the foot is supported by the second layer 108. In other embodiments, such as that of FIG. 9B, the second layer 108 may be designed to support the entire foot or a different proportion of the foot than the embodiment in FIG. 9A. The embodiment of FIG. 9A also depicts a second layer 108 comprising a toe bumper 180 structure positioned at or near the front, toe end 124 of the insole 102, while in other embodiments, a toe stop may be positioned on the feature labeled on the first layer 106. In some embodiments, as described above, there is not a toe

stop. The embodiments of FIGS. 9A-9B may also be used with an outsole 104 configuration.

The embodiments of FIGS. 9A-9B depict an insole 102 that is thicker at the heel end 126 than at the toe end 124. This embodiment may aid in elevating the heel of the wearer. In some embodiments the second layer 108 may be substantially flat or planar, and the first layer 106 may be added to increase the thickness of the insole 102 at or near the heel end 126. In other embodiments, first layer 106 may be added to add thickness to other portions of the sole 100 or insole 102, for example the toe, arch, ball of the foot, and/or heel. In some embodiments, the first layer 106 or second layer 108 define a uniform thickness that defines a planar or substantially flat upper surface for supporting the foot. As described above, compression may change the thickness of the first and/or second subunits in various ways.

There are two embodiments of the presently claimed sole shown in FIGS. 9A and 9B. The embodiment of FIG. 9A has a plurality of shock cavities positioned in the first layer 106, 20 with no shock cavities defined by the second layer 108. The embodiment of FIG. 9B has shock cavities 112 defined by within the second layer 108, but not in the first layer 106. In some further embodiments, both the first layer 106 and the second layer 108 may have shock cavities 112.

25 Leaf-Spring Shocks

In some embodiments, the shocks 114 may define a leaf-spring structure, as depicted in FIGS. 12A-12C. In these embodiments, the leaf spring 190 may be an integral part of the sole 100 as shown in FIG. 12A or may be inserted into 30 leaf spring acceptor structures 192 defined within the surface of the sole 100 as shown in FIG. 12B and the leaf springs 190 may be removable. In some embodiments, shock cavity inserts 116 may be positioned near the leaf spring 190 so that when the leaf spring 190 is compressed toward the surface 35 of the sole 100, it may contact the shock cavity insert 116, as shown in FIG. 12A. In many cases, the shock cavity inserts used in conjunction with the leaf springs 190 may be similar to the shock cavity inserts 116 described above. The embodiments of FIGS. 12A-12C show leaf springs 190 that 40 may be oriented in the same direction; in FIGS. 14A and 14B, the leaf springs 190 may be bowl shaped, and a connector 194 may be used to connect or couple the leaf spring 190 with a portion of the sole 100.

The leaf spring shock embodiments depicted in FIGS. 45 12A-12C each have three sections: two parallel sections 196 that may be substantially parallel to each other and the surface of the sole 100, with a third, non-parallel section 198 positioned between and connecting the two parallel sections 196. As shown in FIG. 12A, in many embodiments, the third connecting section 198 may define an angle ϵ that displaces the second parallel section 196 from first parallel section 196. The first parallel section 196 or second parallel section 196 may be inserted in, connected to, or attached to the surface of the sole 100 using a connector 194 or a leaf spring acceptor structure 192.

FIGS. 14A-14B depicts embodiments of the disclosed leaf spring 190 wherein the leaf spring 190 is curvilinear. In this embodiment, the leaf spring 190 may comprise two planar sections 196 that contact the surface of the sole that 55 are connected by a third, non-planar section 198.

Displacement Translator

The disclosed shock structures 114, which in some embodiments may be positioned between shock cavities 112, may further define a second cavity 200. The embodiments in FIGS. 15A-15B depict these second cavity 200 embodiments. As shown in FIG. 15A, the first layer 106 of 60 an insole 102 may have the second shock cavities 200 that

11

extend from the lower surface 111 of the first layer 106 of the insole 102 and may define a depth that is the same or similar to the depth of the shock cavities 112 of earlier embodiments. In some embodiments, the second shock cavities 200 have a width or depth that is less or smaller than that of the shock cavities 112. In some embodiments, a displacement translator 202 may be inserted into the second shock cavity 200. The displacement translator 202 may be a substantially flat structure (similar to the leaf spring 190 of FIGS. 12A-12B). The displacement translator 202 may be connected to or affixed to a support structure 204, such as a sole support. As shown in FIG. 15B, the support structure 204 may have a plurality of pivots 206 positioned between one or more adjacent shock cavities 200. The pivot 206 embodiment may enable the attachment of a displacement translator 202 to a fixed location by means of a hinge mechanism so as to allow the secondary displacement translator 202 to rotate. The pivot 206 mechanism may be a complementary structure of the displacement translator 202 and thus allows the displacement translator 202 to sit within and rotate about the pivot 206. The pivots 206 may aid in allowing the displacement translator 202 to rotate with, flex, or bend and may aid in translating the flex or bend (and subsequent displacement of the support) to other displacement translators 202. In some embodiments, the second cavity 200 may be referred to as a secondary displacement translator slot, and the displacement translator may be referred to as a secondary displacement translator (SDT). In some embodiments, the displacement translator may not include a second cavity 200, and it may use a shock cavity in place of the second cavity 200. A shock cavity may have both an SDT and a shock insert.

Exemplary embodiments of secondary displacement translators 202 are depicted in FIG. 16A. FIG. 16A shows two embodiments of displacement translators 202, one flat and one "3D." In these embodiments, the first end of the SDT 202 is wider than the second end. In these embodiments, shown in FIG. 16C, the end nearest the top surface of the sole is narrower than the end furthest from the top surface of the sole. The end at or near the surface may be positioned at or near an outer sole.

FIGS. 17A-17B further provide a description for calculating different aspects of the angle of the shock cavities 112, 200 of the contemplated designs based upon certain parameters of an embodiment. Θ_1 may be the angle as measured from vertical of a shock cavity 112, Θ_2 may be the angle as measured from vertical of a second shock cavity 200. Angle α may be the angle from horizontal of the slope of the insole with respect to the heel. In many embodiments, angle Θ_1 and Θ_2 may be from about 0 to about 45 degrees. 17B shows how the insole 102 may compress and deform when exposed to a load such that the practical displacement 216 may be measured.

FIGS. 18A-21B show various shoes incorporating various embodiments of the current disclosure to aid in understanding of how the different improvements may be positioned within a single shoe. FIG. 18A shows a shoe adjacent the ground 101 with an insole 102 and an outsole 104 separated by a barrier 210. FIG. 18B is an enlarged view of a portion of FIG. 18A. The insole 102 may have a first layer 106 and a second layer 108. In the embodiment of FIG. 18A, the first layer 106 does not have any shocks 114 or shock cavities 112. The second layer 108 has both shocks 114 and shock cavities 112. Some shock cavities 112f may be formed through openings 150 between shocks 114 in the upper surface 120 of the second layer 108. Some shock cavities 112g may be formed through openings 150 between shocks

12

114 formed in the lower surface 121 of the second layer 108. The outsole 104 of the shoe may have an upper surface 212 and a lower surface 214. Shock cavities 112h may be formed through openings 150 between shocks 114 in the upper surface 212. Shock cavities 112i may be formed through openings between shocks 114 in the lower surface 214. The lower surface 214 of the outsole 104 may be adjacent the ground 101.

FIG. 19A-19B show another embodiment of a shoe with an insole 102 and an outsole 104. FIG. 19B is an enlarged view of a portion of FIG. 19A. The first layer 106 of insole 102 may have no shocks 114 or shock cavities 112. The second layer 108 of insole 102 may have a plurality of shocks 114, shock cavities 112, shock cavity inserts 116, and displacement translators 202. The shocks 114 shown in FIGS. 19A-19B may have a variety of widths or thicknesses. In addition, some shock cavities, formed through the openings 150 between the shocks 114 may have a variety of widths. Shock cavity 112j may be formed through opening 150 in the upper surface 120 of the second layer 108, and a shock cavity insert 116d and a displacement translator 202a may be positioned within the shock cavity 112j. In another example, shock cavity 112k may be formed through opening 150 in the lower surface 121 of the second layer 108, and only a shock cavity insert 116e may be positioned within or adjacent to it. Outsole 104 may have shock cavities 112l and 112m formed through openings 150 in the upper surface 212. Shock cavity 112m may be filled with shock cavity insert 116f and displacement translator 202b. Shock cavity 112l may only be filled or adjacent to shock cavity insert 116g. Shock cavity 112n may be formed through openings 150 in the lower surface 214 between shocks 114. In some embodiments, a secondary displacement translator may be inserted through opening 150 in the lower surface 121 of the second layer 108.

FIGS. 20A-20B show another embodiment of a shoe with an insole 102 and an outsole 104. The second layer 108 may have a plurality of shocks 114 and shock cavities 112 formed between. For example, shock cavity 112p may be formed in the upper surface 120 between shocks 114 and have shock cavity insert 116g positioned within. Shock cavity 112o (FIG. 20B) may also be formed in the upper surface 120 between shocks 114 and have shock cavity insert 116h and secondary displacement translator 202c positioned within. The lower surface 121 may be positioned adjacent a leaf spring system 190. Shock cavity 112q may be formed in the lower surface 121 between shocks 114 and have shock cavity insert 116i and a portion of the leaf spring 190a positioned within. The outsole 104 may have shock cavities 112s (FIG. 20B) formed in the upper surface 212 with secondary displacement translators 202d positioned within. The outsole 104 may also have shock cavities 112r formed in the upper surface 212 with shock cavity inserts 116j and secondary displacement translators 202e positioned within.

FIGS. 21A-21B show another embodiment of a shoe with an insole 102 and an outsole 104. The second layer 108 may have a plurality of shocks 114 and shock cavities 112 formed between. Leaf spring system 190b may be positioned between the first layer 106 and the second layer 108. A portion of the leaf spring 190b may be positioned within shock cavity 112t along with shock cavity insert 116k. In some examples, shock cavity 112u may have only shock cavity insert 116l positioned within it. Leaf spring system 190c may be positioned between the second layer 108 and the barrier 210. Shock cavity 112v may extend from the lower surface 121 of second layer 108 and have a portion of leaf spring system 190c and 116m positioned within. Leaf

13

spring system 190d may be positioned between the barrier 210 and the upper surface 212 of the outsole 104. Shock cavities 112x may have a portion of the leaf spring system 190d and 116o positioned within. Some shock cavities 112w may only have the portion of the leaf spring 190d positioned within. 5

Swappable Insole

Yet another embodiment is wherein the insoles can be swapped between different degrees of firmness from relatively soft to extra firm. The ability to swap the insole gives a user the ability to experience a range of foot sensations up to feel of barefoot walking or running. If insole is extra firm and flat, It can give a feeling of walking or running barefooted, regardless of shoe fitting. 10

Bumpered Insoles

Another aspect of the current disclosure is an embodiment that allows a user to convert larger insoles to fit smaller shoes, and to convert larger shoes sizes to fit smaller feet. The purpose of this innovation is to initially reduce tooling costs by reducing number of manufactured shoe sizes and also reduce inventory costs. A strip of padding bumper can be added to the top surface of an insole on the front side of the toes along the insole's front (toe side) circumference. In one embodiment, the bumper may cover a lateral depth of up to 1/2 or 1 shoe size corresponding to shoe size of 9 1/2 and 9, as an example. In another embodiment, the bumpered insole would also comprise integral cutting marks at the front and the rear of the insole to allow for the original insole to be trimmed down to accommodate a smaller shoe size. 15

While multiple embodiments are disclosed, still other embodiments of the present disclosure will become apparent to those skilled in the art from the following detailed description. As will be apparent, the disclosure is capable of modifications in various obvious aspects, all without departing from the spirit and scope of the present disclosure. 35 Accordingly, the detailed description is to be regarded as illustrative in nature and not restrictive.

All references disclosed herein, whether patent or non-patent, are hereby incorporated by reference as if each was included at its citation, in its entirety. In case of conflict 40 between reference and specification, the present specification, including definitions, will control.

Although the present disclosure has been described with a certain degree of particularity, it is understood the disclosure has been made by way of example, and changes in 45 detail or structure may be made without departing from the spirit of the disclosure as defined in the appended claims.

We claim:

1. A device for increasing the comfort of a shoe, the 50 device comprising a sole comprising:
  - a layer having a first surface, a top surface, a toe end, and a heel end;
  - a plurality of shocks disposed throughout the layer between the toe end and the heel end, each of the 55 plurality of shocks extending away from the first surface of the layer, the plurality shocks defining a first end positioned at or near the first surface of the layer and a second end positioned away from the first surface of the layer, wherein each of the plurality shocks are connected to each other at the second end, and each of the layer plurality of shocks extending away from the first surface of the layer at a shock angle;
  - a shock cavity defined by two adjacent shocks of the 60 plurality of shocks and the first surface of the layer; wherein when the device is in a compressed position, the shock cavity collapses and the device is configured to redirect a heel of the foot away from a heel end of the item worn on the foot to reduce contact of the heel of the foot with the item worn on the foot.

14

redirect a heel of a user's foot away from a heel end of the shoe to reduce contact of the heel of the user's foot with the shoe; and

wherein the sole is an insole configured to be positioned within the shoe, wherein the insole is configured to lie along a footbed of the shoe, the top surface of the layer of the insole is configured to contact a user's foot, and the second ends of the respective shocks are configured to contact the footbed.

2. The device of claim 1, further comprising at least one displacement translator positioned within at least one cavity, and at least one support structure, wherein the displacement translator is substantially flat and connected to the support structure. 10

3. The device of claim 1, further comprising a first shock cavity insert positioned within a portion of the shock cavity. 15

4. The device of claim 1, wherein a dimension of the shock cavity varies.

5. The device of claim 1, further comprising a second shock cavity. 20

6. The device of claim 5, wherein the shock cavity and the second shock cavity are dissimilarly shaped.

7. The device of claim 5, further comprising a first shock cavity insert positioned within a portion of the shock cavity and a second shock cavity insert positioned within a portion of the second shock cavity. 25

8. A device configured to modify the shock impact absorption properties of an item worn on a foot, the device comprising: 30

a sole having a layer with a first end, a second end, a first surface and a second surface opposite the first surface, wherein the sole is an insole configured to be positioned within the item worn on the foot, wherein the insole is configured to lie along a footbed of the item worn on the foot, wherein the second surface is configured to contact the foot with

a plurality of shocks disposed throughout the layer between the first end and the second end, each of the plurality of shocks extending away from the first surface and between the first end of the layer and second end of the layer, wherein each shock includes a lower portion of the shock located adjacent to the first surface of the sole;

an upper portion of the shock located away from the first surface of the sole, the upper portion of the shock configured to contact the footbed of the item worn on the foot, wherein each of the plurality shocks are connected to each other at the upper portion;

a depth extending from the lower portion to the upper portion; and

a shock angle, wherein each shock extends away from the first surface of the layer at the shock angle; a shock cavity defined by the two shocks and the first surface of the layer; and

wherein when the device is in a compressed position, the shock cavity collapses and the device is configured to redirect a heel of the foot away from a heel end of the item worn on the foot to reduce contact of the heel of the foot with the item worn on the foot.

9. The device of claim 8, further comprising a toe bumper positioned at the first end of the sole and extending away from the second surface in a direction away from the first surface. 65

10. The device of claim 1, wherein the shock cavity is cylindrical.

15

11. The device of claim 8, wherein the shock angle is between 0 degrees and 45 degrees.

12. A device for increasing the comfort of a shoe, the device comprising a sole comprising:

a layer having a first surface, a top surface, a toe end, and a heel end;

a plurality of shocks disposed throughout the layer between the toe end and the heel end, each of the plurality of shocks extending away from the first surface of the layer, the plurality shocks defining a first end positioned at or near the first surface of the layer and a second end positioned away from the first surface of the layer, wherein each of the plurality shocks are connected to each other continuously from the first end to the second end, and each of the plurality of shocks extending away from the first surface of the layer at a shock angle;

10
15

16

a shock cavity defined by two adjacent shocks of the plurality of shocks and the first surface of the layer; a shock cavity insert positioned within a portion of the shock cavity, wherein the shock cavity insert is adjustable;

wherein when the device is in a compressed position, the shock cavity collapses and the device is configured to redirect a heel of a user's foot away from a heel end of the shoe to reduce contact of the heel of the user's foot with the shoe; and

wherein the sole is an insole configured to be positioned within the shoe, wherein the insole is configured to lie along a footbed of the shoe, the top surface of the layer of the insole is configured to contact a user's foot, and the second ends of the respective shocks are configured to contact the footbed.
